UNITED STATES PATENT OFFICE.

WILLIAM P. QUENTELL, OF NEW YORK, N. Y.

PROVING-SHEET.

1,295,597.

Specification of Letters Patent.

Patented Feb. 25, 1919.

Application filed June 25, 1918. Serial No. 241,743.

To all whom it may concern:

Be it known that I, WILLIAM P. QUENTELL, a citizen of the United States, residing at New York, in the county of New York and 5 State of New York, have invented or discovered certain new and useful Improvements in Proving-Sheets, of which the following is a specification, reference being had therein to the accompanying drawing.

10 The object of this invention is to provide a proving sheet or checking slip for recording items as they are posted in ledgers or other account books, and with this object in view I use a sheet or slip of about the width of 15 that part of the account sheet which is ruled for the figures of the items, the said sheet or slip being marked in such a manner that the operator, when placing it on an account sheet or ledger leaf, can readily bring a pre- 20 determined portion of the proving sheet over or cause it to register with any desired portion of the account sheet or ledger leaf. The proving sheet or slip, in its preferred form, has on one side a transfer material, such, for 25 example, as used on so-called "carbon paper", so that when said sheet or slip is placed over the account sheet or ledger leaf and the item to be posted is written with a pencil or pen on the proving sheet or slip the item is 30 reproduced through the transfer material on to the account sheet or ledger leaf. By so posting accounts a facsimile record is obtained on the proving sheet or slip of the items thus posted, and may then be com- 35 pared with the documents from which the items were copies, and errors, if any, can thus be detected.

The transfer material may be applied directly to the back face of the proving sheet 40 or checking slip, or "carbon paper" may be pasted or otherwise fastened to the back of said proving sheet or slip in any suitable manner, with the "carbon" face, or the face having the transfer material, out. As the 45 continuous handling of the "carbon" side of the proving sheet while posting is liable to soil the operator's fingers, and as marks may accidentally be made on the account sheet or ledger leaf by the pressure of the operator's 50 hand resting on said proving sheet or slip while writing, I preferably employ a guard to protect the user's fingers and the account sheet or ledger leaf. This guard is preferably in the form of a flattened tube made 55 of flexible material of light weight and through which tube the proving sheet or slip

will run freely so that it may be easily adjusted to suit the user's convenience.

The proving sheet or checking slip is preferably provided with a plurality of spaced 60 openings or windows through which the vertical lines on the account sheet or ledger sheet may be seen, and is also preferably provided with a heavy line or double lines which, by means of said openings, or windows, 65 may be brought into register with some corresponding line or lines on the account sheet or ledger leaf, so that the figure items to be written on the proving sheet or checking slip and to be transferred to the 70 account sheet or ledger leaf may be brought into proper or desired positions on the account sheet or ledger leaf. The proving sheet or slip may also have lighter vertical lines and horizontal lines for convenience in 75 causing said sheet or slip to properly register with corresponding lines on the account sheet or ledger leaf, but these lighter lines are not positively necessary and may be omitted if desired. The openings or windows 80 referred to may be simply cut out places in the proving sheet or slip, or they may be places made transparent as in "window" envelopes.

In the accompanying drawing Figure 1 85 is a face view of the improved proving sheet or checking slip; and Fig. 2 is an edge view thereof. Fig. 3 is a partial face view of the same with a preferred form of guard applied thereto. Fig. 4 is a section on line 90 4-4 of Fig. 3; and Fig. 5 is a view similar to Fig. 4 illustrating a slightly modified form of guard.

Referring to the drawing, 12 denotes the improved proving sheet or checking slip having spaced transverse openings or windows 95 13. These transverse openings or windows 13 extend laterally across a considerable portion of the sheet 12, so that the vertical lines of the account sheet or ledger leaf may be 100 readily seen through said openings or windows. The front face of said sheet or slip has a prominent vertical line or double lines 14 and is preferably ruled with a series of lighter vertical lines 15 and horizontal lines 105 16, these lines being formed on the front face *a* of said sheet or slip. The back face *b* of the proving sheet or slip 12 is provided with a suitable transfer material which, as heretofore stated, may be applied directly 110 to the said sheet or slip, or may be on a separate sheet or slip pasted or otherwise at-

tached to the sheet or slip 12. In other words the coating or surface of transfer material may be applied directly to the back of the proving sheet 12 or may be on a separate sheet or slip pasted or otherwise suitably attached to the sheet 12.

To prevent the fingers of the user and the account sheet or ledger leaf from being soiled by the pressure of the hand in holding the proving sheet or slip against the account sheet or ledger leaf a guard consisting preferably of a tube of thin flexible material, as rather heavy paper or rubber cloth, and through which guard the proving sheet or slip may readily run, is preferably employed. In using the improved proving sheet or slip said sheet or slip and the guard are grasped by the thumb and fingers of the user to hold the said sheet or slip against the account sheet or ledger leaf, and the said guard thus prevents the fingers of the user from being soiled by the transfer material used in connection with the proving sheet or slip, and also prevents the account sheet or ledger leaf from being soiled by the pressure of the steadyng fingers of the writer, as these fingers will rest on the guard in the writing operation, and not directly on the proving sheet or slip. The guard is loosely mounted with reference to the proving sheet or slip so that it may be moved lengthwise of the latter as the writing progresses. This guard, in its preferred form, consists of a flattened tube 17, as shown in Figs. 3 and 4, loosely receiving the check slip 12, or it may consist merely of a folded piece of paper or other flexible fabric 17^a, as shown in Fig. 5.

In the use of the invention the proving sheet or slip is placed on the account sheet or ledger leaf and is brought into proper register, by means of the openings or windows 13, and by one edge, or by the vertical line or lines on its face, with the proper spaces on the account sheet or ledger leaf,

and the figure items are then written with a pencil or pen on the proving sheet or slip, and of course are also written in facsimile on the account sheet or ledger leaf. When the posting has been completed the proving sheet or slip may be filed away for future reference and affords a checking duplicate of the figure items which have been entered on the account sheet or ledger leaf.

Having thus described my invention I claim and desire to secure by Letters Patent:

1. A proving sheet or slip having a plurality of spaced transverse windows and having also a surface of transfer material on its back, said sheet or slip being provided with suitable indicating means whereby it may be conveniently brought into register with certain lines or spaces on an account sheet or ledger leaf visible through said windows.

2. A proving sheet or slip having a plurality of spaced transverse windows and having also a surface of transfer material on its back, said sheet or slip having on its face suitable lines whereby it may be conveniently brought into register with certain lines or spaces on an account sheet or ledger leaf visible through said windows.

3. A proving sheet or slip having a plurality of spaced transverse windows and having also a surface of transfer material on its back, combined with a flexible guard loosely mounted with reference to said sheet or slip so that said guard may be moved lengthwise of said sheet or slip.

4. A proving sheet or slip having a plurality of spaced transverse windows and having a surface of transfer material on its back, combined with a flexible guard consisting of a flattened tube through which said sheet or slip may run freely.

In testimony whereof I affix my signature.

WILLIAM P. QUENTELL.
